UNITED STATES PATENT OFFICE.

JENNIE R. McCORMICK, OF WICHITA, KANSAS.

FUR-CLEANING PROCESS.

No Drawing.

Application filed December 18, 1922. Serial No. 607,873.

To all whom it may concern:

Be it known that JENNIE R. McCORMICK, a citizen of the United States of America, residing at Wichita, in the county of Sedgwick and State of Kansas, has invented certain new and useful Improvements in Fur-Cleaning Processes, of which the following is a specification.

My invention relates to process for removing face cream and powder from the outside surface of fur.

The compound consists of a mixture of benzol, chloroform and extract of bergamot in the following proportions:

	Parts.
Benzol	83
Chloroform	16
Extract of bergamot	1

In making the compound the ingredients are thoroughly mixed in any suitable manner and receptacle and then bottled for use.

In using the compound the fur is rubbed both ways with cloth dipped in the fluid, the fur being brushed smooth after cleaning. The fur or garment is then turned and the 25 silk lining cleaned in a similar manner.

Having thus described my invention:

What I claim as new and desire to secure by Letters Patent is:

The herein described process of cleaning 30 fur consisting in rubbing the fur both ways with a cloth dipped in a mixture of substantially 83 parts benzol and substantially 16 parts chloroform.

In testimony whereof I affix my signature 35 in presence of two witnesses.

JENNIE R. McCORMICK.

Witnesses:

E. E. BUTTS,

B. W. GAAR.
